Primary Examiner—Catherine Tuttle

(74) *Attorney, Agent, or Firm*—Banner & Witcoff, Ltd.

(57) **CLAIM**

The ornamental design for a bottle, as shown and described.

DESCRIPTION

FIG. 1 is a front perspective view of a bottle showing a first embodiment of our new design;

FIG. 2 is a front view thereof;

FIG. 3 is a right view thereof;

FIG. 4 is a rear side view thereof;

FIG. 5 is a left side view thereof;

FIG. 6 is a top view thereof;

FIG. 7 is a bottom view thereof;

FIG. 8 is a front perspective view of a bottle showing a second embodiment of our new design;

FIG. 9 is a front view thereof;

FIG. 10 is a right view thereof;

FIG. 11 is a rear side view thereof;

FIG. 12 is a left side view thereof;

FIG. 13 is a top view thereof; and,

FIG. 14 is a bottom view thereof.

The circles formed by uneven length dashes represent unclaimed boundaries of the claimed design. The evenly dashed lines remaining are included for the purpose of illustrating portions of the bottle that form no part of the claimed design.
